UNITED STATES PATENT OFFICE

163,888

COVER FOR COSMETIC BOTTLES AND THE LIKE

Harold Merillat, New York, N. Y.

Application October 9, 1950, Serial No. 12,493

Term of patent 14 years

(Cl. D86—10)

To all whom it may concern:

Be it known that I, Harold Merillat, a citizen of the United States of America, residing at New York city, in the county of New York and State of New York, have invented a new, original, and ornamental Design for Covers for Cosmetic Bottles and the like, of which the following is a specification, reference being had to the accompanying drawing, forming part thereof.

In the drawing

Fig. 1 is a front perspective view of a cover for cosmetic bottles and the like, showing my new design.

Fig. 2 is a rear perspective view thereof.

The cover is open at the bottom and fits over the whole bottle.

I claim:

The ornamental design for a cover for cosmetic bottles and the like, substantially as shown and described.

HAROLD MERILLAT.
